UMBRELLA

Guillermo Solomon, Santiago, Dominican Republic

Application December 10, 1938, Serial No. 244,971

8 Claims. (Cl. 135—20)

This invention relates to umbrellas and particularly to an improved inflatable umbrella, an object being to provide a construction which is simple and which may be readily nested in a small closed receptacle when not in use.

Another object of the invention is to provide a collapsible umbrella with the canopy portion made of rubber and the other parts of various materials and arranged to act both as a pump for inflating the canopy and as a handle.

A further object, more specifically, is to provide in a collapsible umbrella a canopy portion made of inflatable rubber and associated with a tubular container and a piston which uses the container as a cylinder for compressing and directing the air into the canopy to inflate the same.

In the accompanying drawings—

Fig. 1 is a longitudinal vertical sectional view of an umbrella disclosing an embodiment of the invention, with the parts shown in nested position;

Fig. 2 is an enlarged fragmentary sectional view showing the deflating valve illustrated in Fig. 1;

Fig. 3 is a sectional view through Fig. 2 approximately on the line 3—3;

Fig. 4 is an enlarged fragmentary sectional view through Fig. 1 approximately on the line 4—4;

Fig. 5 is a vertical sectional view through the umbrella when in use;

Fig. 6 is a top plan view of the umbrella when in use, the same being on a reduced scale;

Fig. 7 is an enlarged fragmentary sectional view through Fig. 6 approximately on the line 7—7;

Fig. 8 is an enlarged fragmentary sectional view through Fig. 6 approximately on the line 8—8.

Referring to the accompanying drawings by numerals, 1 indicates a casing which forms part of the handle when the umbrella is in use. In this casing, when the parts are nested, is a canopy 2 which is adapted to be inflated to appear as shown in Figs. 5 and 6. The canopy 2 is made from an upper and a lower sheet of thin rubber 3 and 4 cemented or vulcanized together at 5, and carrying at their inner ends thickened zones 6 and 7 for reinforcing purposes. In connecting the top and bottom members 3 and 4 of the canopy 2, the parts are preferably vulcanized together when the portion 5 is exterior and then the entire device is turned inside out so that the parts will appear as shown in Fig. 5.

In Fig. 1 the canopy is shown as collapsed and arranged in the handle or casing 1. In this view the vulcanized ends 5 and certain vulcanized lines shown in Figs. 6 to 8 inclusive have been eliminated for the purpose of clearance. However, in Fig. 1 it will be seen that there is provided a cap 8 which is threaded at 9 into a sleeve 10 having large threads 11. A piston rod 12 is fitted into the bore 13 of cap 8 and secured thereto by cement or in any other desired manner. A valve seat 14 is arranged at the end of the rod 12, said valve seat having an opening 15, as shown in Fig. 2, which is adapted to be closed by a soft rubber valve member 16 connected to the lower end 17 of a ring 18. This ring is provided with V-shaped members 19 and 20 which coact with a pin 21'. The ring 18 is of spring metal and normally is in the position shown in Fig. 1. The fact that the portions 21 and 22 tend to move together, as shown in Fig. 1, causes the members 19 and 20 to act on the pin 21' to pull the valve member 16 against its seat. When it is desired to deflate the canopy 2, ring 18 is pushed downwardly to the position shown in Fig. 2, whereupon the same action of the portions 21 and 22 will tend to hold the valve open.

From Fig. 1 it will be seen that the rod 12 is provided with a longitudinal passageway 23 into which the valve 16 extends and which merges into sight apertures 24 and 25, whereby air interior of the canopy 2 may readily escape when the valve 16 is open. It will be noted that a cord or other element 26 binds the canopy to the rod 12 around the bore 13 and a similar cord or ligament 27 binds the lower part to the rod 12 immediately below the inlet valve 28. This valve is provided with rubber valve members 29 and 30. The valve members 29 and 30 are connected by a resilient piece of rubber 31, or if desired a coil spring could be used whereby the valves normally rest against their seats 32 and 33 screwed into suitable apertures in the rod 12. It will be observed that there is provided a longitudinally extending inlet bore or air passageway 34' which extends from the valve seats 32 and 33 downwardly, as shown in Fig. 1, and through a bottom washer 34 and associated parts. A cap 35 of any desired material is screwed into the casing 1, which casing may be metal. The cap 35 may also be metal, rubber, wood, or other suitable material. The washer 34 with its associated parts, including the rod 12, forms a pump piston and includes an externally threaded knob 36 having a washer 37 preferably of metal. A second metal washer 38 is held in place by a nut 39.

screwed on to the lower end of the rod 12. In this way all the parts are rigidly secured together.

When it is desired to use the umbrella, the cap 8 at the top, as shown in Fig. 1, is unscrewed 5 and the parts are pulled out until the entire canopy is exterior of the casing 1. The rod 12 may be grasped, or cap 8 may be grasped, and the piston including the washer 34 reciprocated, whereupon it will act as a pump piston and force 10 air from casing 1 upwardly through the passageway 34 and out through the inlet valves 29 and 30 into the interior of the canopy 2. This action continues for a short time or until the canopy is fully inflated, as shown in Fig. 5. After the 15 canopy has been fully inflated, the knob 36 is moved upwardly and screwed into the sleeve 10, as shown in Fig. 5, whereupon the umbrella is ready for use.

When it is desired to nest the umbrella, as 20 shown in Fig. 1, the wire handle 18 is depressed to the position shown in Fig. 2 and the air will immediately begin to escape. If desired, the canopy may be squeezed between the ends to force the air out quickly and then the knob 36 is 25 unscrewed and the parts forced into the casing 1, as shown in Fig. 1. After this has been done the cap 8 is screwed into place and the handle 18 pulled upwardly.

In making the canopy, upper and lower sheets 30 of elastic rubber are used and in order to give the desired appearance and stiffness to the rubber sheets they are vulcanized along certain lines, for instance, a number of lines 40 are vulcanized, from the periphery to the thickened portion 6. 35 In Fig. 6 eight of these lines have been provided. As shown in Fig. 8, these lines connect the top and bottom sheets of rubber for the full distance between the thickened parts 6 and 7 and the periphery. Auxiliary lines 41 and 42 are provided 40 between the principal lines of vulcanization, said auxiliary lines being vulcanized particularly as indicated in Fig. 7. These auxiliary lines connect the top and bottom sheets of rubber together in the same way as the principal lines 40 45 but extend for a less distance inwardly from the periphery. In this way the periphery is stiffened by the vulcanized edges 5 and the various radial lines of vulcanization just described, while the center is stiffened by the thickened or reinforced 50 portions 6 and 7, whereby when the canopy is inflated it will appear substantially as shown in Figs. 5 and 6.

When the parts are nested, as shown in Fig. 1, the umbrella is so small that it may readily be 55 carried in the hand bag or possibly in the pocket of the wearing apparel of the person using the umbrella.

I claim:

1. An inflatable umbrella including a casing 60 closed at one end and provided with a threaded sleeve at the outer end, a piston arranged in said casing having a threaded portion adapted to be screwed on to said threaded sleeve when coacting with said casing to function as a handle, a piston rod connected with said piston and adapted to be moved for reciprocating the piston to provide compressed air, said rod having a passageway partly therethrough, an inflatable 65 canopy connected with said rod and positioned to receive air from the passageway in the piston, and a valve for preventing the return of air from the canopy to the rod, whereby when the canopy has been fully inflated said piston is adapted to be 70 screwed on to said threaded member and the rod 75 and the casing act as an umbrella handle.

2. An umbrella of the character described including a casing closed at one end and open at the other end, a threaded sleeve in the open end, a piston having a washer engaging the interior side walls of the casing, a knob having threads 10 adapted to be screwed into said threaded sleeve, a stem connected with said knob, and a collapsible canopy carried by the outer end of said stem, said canopy and stem being insertable into said casing.

3. An umbrella comprising an inflatable canopy formed with top and bottom members connected together at the periphery, said top and bottom members being reinforced centrally, said canopy having the top and bottom members connected 15 together in radially spaced lines at the outer part, a stem extending through the center of the inner part, means for connecting the canopy to said stem, said stem being partly hollow and provided with an opening discharging into the canopy, an 20 outwardly opening valve arranged in said opening to normally maintain the same closed, and means coacting with the stem forming a pump for forcing the air through the stem past said valve into the canopy.

4. In an umbrella of the character described, a canopy formed of upper and lower sheets of rubber with the central part thickened to provide a reinforced zone, said upper and lower parts being vulcanized together at the periphery with 25 the vulcanized part extending inwardly, said canopy also being provided with a plurality of lines of vulcanization connecting the top and bottom parts together from the thickened portion to the periphery, and a second series of radially extending vulcanized lines connecting the top and bottom parts together from the periphery 35 inwardly radially different distances.

5. An umbrella comprising an inflatable canopy, a stem for said canopy, said stem being provided with a longitudinally extending bore at each end, both of said bores having openings discharging into the interior of said canopy, a valve for each of said openings, manually actuated means for moving one of said valves to an 45 open position for discharging the air from the canopy and the other of said valves automatically opening inwardly when pressure is brought to bear thereon and automatically moving to a seat when the pressure is relieved, and means for 50 directing air under pressure through one of said bores to the last-mentioned valve for inflating said canopy.

6. An umbrella of the character described comprising an inflatable canopy, a stem connected to 55 the canopy centrally thereof, said stem having a bore opening into the canopy and an outwardly opening valve arranged at the end of said bore for permitting the escape of air from the bore into the canopy but preventing the return of air 60 into the bore, means at the end of the stem forming a piston, and means coacting with the piston forming a cylinder whereby when said last-mentioned means is reciprocated in respect to the piston air will be forced into the canopy for 65 inflating the same.

7. In an umbrella of the character described, a collapsible canopy, a stem connected to said canopy centrally thereof, a knob having exterior threads connected to the end of said stem, a tubular member having a threaded sleeve into which 70 said knob is adapted to be threaded, said tubular member acting as a handle for said stem when the knob is screwed into said threaded member, said threaded member adapted to be unscrewed 75

and moved to the bottom of said tubular member, said tubular member also being of a size to receive said stem and canopy when collapsed, and a sealing cap carried by the outer end of said stem and adapted to be screwed into said threaded member when the canopy and stem have been nested in said tubular member.

8. An umbrella of the character described comprising a stem provided with a handle, an inflatable canopy connected to said stem, said stem having a passageway leading from the interior of the canopy to a point exterior thereof, for venting the canopy when it is desired to collapse the same, a valve seat forming part of said passageway, a cone-shaped valve member adapted to rest

on said seat for preventing the passage of air, and means for moving said valve member to an unseated position or a seated position and then holding the same in either of said positions, said means including a pin stationary in respect to said stem and a resilient ring having a number of facing V-shaped portions, an extension from one of said V-shaped portions connected with said valve member whereby when said V-shaped portions are arranged inwardly of said pin the valve member will be held open and when arranged outwardly of said pin they will coact with the pin for holding the valve member closed. 5 10
